F.A. Pratt.

Design for Metal Drill.

N° 4,439.

Fig. 1

Patented Oct. 25, 1870.

Fig. 2.

*Inventor.
Francis A. Pratt*

United States Patent Office.

FRANCIS A. PRATT, OF HARTFORD, CONNECTICUT, ASSIGNOR TO THE PRATT & WHITNEY COMPANY, OF SAME PLACE.

Design No. 4,439, dated October 25, 1870.

DESIGN FOR A DRILLING-MACHINE.

The Schedule referred to in these Letters Patent and making part of the same

To all whom it may concern:

Be it known that I, FRANCIS A. PRATT, of the city and county of Hartford and State of Connecticut, have originated or discovered certain new Improvements in Design for Vertical Drilling-Machine; and to enable others skilled in the art to make and use the same I will proceed to describe it, referring to the drawing making part of this specification, in which the same letters indicate like parts in each of the figures.

In the accompanying drawing—

Figure 1 is a front elevation.

Figure 2 is a side elevation.

a is a hollow column.

b is a supporting-column.

c is a bed-plate.

d is an arm for supporting the table.

e is a movable head for supporting the spindle.

f is a drilling-table.

g g are cone pulleys.

h h' are tight and loose pulleys.

i is a feed-gear plate or receiver.

j is a hand feed-wheel.

k k are feed-cones.

m m are table-elevating apparatus.

o is a stand and grooved wheel for counterbalancing mechanism.

p is a drill-spindle.

r is a feed-shaft.

s is a belt-slipping apparatus.

t t are bevel gears.

The whole is intended as a new design for a single spindle vertical drilling-machine.

I do not claim in this application any novelty in the construction or combination of the mechanism herein described; but

What I do claim as my invention, and desire to secure by Letters Patent, is—

The design for a single spindle vertical drilling-machine, substantially as shown and described.

FRANCIS A. PRATT.
